UNITED STATES PATENT OFFICE.

JAMES ORLAND BECHDOLT, OF PORTLAND, INDIANA.

HOG-HOLDER.

959,422.

Specification of Letters Patent. Patented May 24, 1910.

Application filed May 22, 1908. Serial No. 434,377.

To all whom it may concern:

Be it known that I, JAMES ORLAND BECHDOLT, a citizen of the United States of America, residing at Portland, in the 5 county of Jay and State of Indiana, have invented new and useful Improvements in Hog-Holders, of which the following is a specification.

This invention relates to hog holders and 10 has for its object to provide a device of the character referred to embodying in connection with a suitable handle, a flexible and extensible band combined with operating means therefor and employed in connection 15 with a snout block, whereby the band may be quickly clamped around the snout of a hog and drawn taut to securely hold the animal.

With the above and other objects in view 20 the invention consists in the novel construction combination and arrangement of parts herein fully described illustrated and claimed.

In the accompanying drawings, Figure 1 25 is a side elevation of the improved holder. Fig. 2 is a longitudinal section of the same. Fig. 3 is a detail perspective view of the snout block.

Referring to the drawings 1 designates a 30 tubular handle of any suitable length in which is mounted a slide rod 2 provided at one end with an operating handle 3 and provided at the opposite end with an eye or aperture 4.

5 designates a flexible band which may 35 consist of a suitable length of wire having one end securely fastened through the eye 4 of the slide rod 2.

6 designates a snout block provided with 40 a tubular boss 7 internally bored as at 8 to receive and fit upon one end of the tubular handle 1 to which it is secured by means of a rivet 9 or its equivalent. The snout block thus rigidly secured to and around the tubular handle 1, is provided with an oblique 45 guide-way 10 through which the adjacent end portion of the band 5 is adapted to slide freely as the rod 2 is moved lengthwise within the handle 1. In other words, the 50 snout block has a continuous passage into one end of which the handle 1 fits so that the bore of the handle forms with the oblique portion 10 of the passage in the block, a continuous unbroken guide-way for the 55 operating rod 2 and the movable end of the band 5. By having the guide-way disposed

obliquely to the axis of the handle 1 or at an acute angle to the snout engaging face of the block 6, the portion of the band which moves in and out of the guide-way is disposed more closely in tangential relation to the snout engaging face of the block. The snout block is provided with a lateral extension or offset 11 at one side and said extension is provided with a hole 12 to receive the other end of the flexible band 5 which is secured therein in any suitable manner as illustrated in Figs. 1 and 2 of the drawings. The snout engaging face forms in effect a part of a continuous ring, 70 the major portion of which consists of the band, and because of the peculiar construction of the block and relation of the band thereto, a firm hold can be obtained on the snout.

In operation, the handle 1 is grasped in one hand and the other handle 3 is grasped in the other hand. Sufficient slack is given to the band 5 to enable it to be placed around the snout of the hog, and as soon 80 as this is effected, the slide bar 2 is drawn outward so as to close the band 5 holding it tightly around the snout thereby obtaining a secure hold on the animal, the snout block 6 forming a rest for the animal's snout 85 while the oblique guideway 10 provides for a smooth and easy sliding action of the band 5 through the snout block.

I claim:—

1. A hog holder comprising a tubular 90 handle, a snout block having a passage extending entirely through the same and into one end of which the handle is secured, the remaining portion of the passage being disposed obliquely to the axis of the handle and 95 at an acute angle to the snout engaging face of the block and coöperating with the bore of the handle rod to form a continuous guide-way, a slide rod movable longitudinally in the handle and terminating short 100 of the snout block, an approximately circular flexible band having one end connected with the snout block at one side of the axis of the handle and the other end extending into the guide-way of the snout block at a 105 point disposed to the opposite side of the axis of the handle and connected with the slide rod, the snout engaging face of the block coöperating with the band to form substantially a continuous snout engaging 110 means.

2. A hog holder comprising a tubular

handle, a snout block having a passage composed of two portions, one arranged approximately at right-angles to the snout engaging face of the block and the other at an acute angle thereto, means for securing the handle in the first mentioned portion of the passage of the block, whereby the second mentioned portion of the passage coöperates with the bore of the handle to form a continuous guide-way, the obliquely disposed portion of the passage having its open end terminating in the snout engaging face of the block at one side of the axis of the handle, said block having a lateral projection disposed at the opposite side of the axis of the handle from the said open end of the

passage, a flexible band having one end secured to the extremity of the projection and the other end slidably extending into the passage of the block, and an operating rod 20 slidable in the handle and connected with the movable end of the band, the portions of the band adjacent the block being disposed approximately in tangential relation to the snout engaging face of the block. 25

In testimony whereof I affix my signature in presence of two witnesses.

JAMES ORLAND BECHDOLT.
